UNITED STATES PATENT OFFICE

CHARLES W. EBELING, OF NEW YORK, N. Y., ASSIGNOR TO HARRISON W. ROGERS,
INCORPORATED, A CORPORATION OF DELAWARE

SYNCHRONIZED PHOTOGRAPHY AND SOUND RECORDING AND REPRODUCING

Application filed November 28, 1927. Serial No. 225,857.

This invention relates to improvements in synchronized photography and sound recording and reproducing, one object of the invention being the provision of a mechanism in which, in conjunction with a projecting machine or camera, there are employed switches, controlled by the film, to select, for setting in motion, sound reproducing mechanisms or recording mechanisms, as the case may be, and for electing the electrical recording or amplifying circuit to be controlled from the sound recording or reproducing machine, the present construction being an arrangement for two sound reproducing or recording machines so that a continuous action in the recording or reproducing of sound may be attained.

Broadly speaking, there are two sound reproducing machines for operation, one at a time, two film-controlled switches for starting and stopping the respective sound reproducing machines, and two separate means under the control of each sound reproducing machine, whereby such machine has selective means for electing which machine will be controlled by the film controlled switches and which machine will be connected to the recording or amplifying circuit.

In the accompanying drawings:

Fig. 1 is a diagrammatic view showing all of the circuits used in conjunction with the present invention;

Fig. 2 is a top plan view of a portion of one of the sound reproducing machines and its pickup carrying arm;

Fig. 3 is a top plan view, on a large scale, of one of the switches controlled by the pickup arm;

Fig. 4 is a view in elevation, showing the switch attached to the supporting arm;

Figs. 5, 6 and 7 are detailed views of the switch and actuating member.

In describing the present invention, the various circuits will be described in their order to clarify the complete operation, there being two sound reproducing machines, Nos. 1 and 2, and a projector P, the former being indicative of any sound recording or reproducing machines, while the latter is indicative of the camera or projector.

Each sound reproducing machine consists of a turntable 5—6, supporting the respective pickup carrying arms 7 and 8, each one of which is provided with its respective pickup 9 or 9'. This pickup is any form of electrical translator which will act both to record and reproduce and may be of a magnetic or inductive type.

Film controlled circuit: One of these circuits, which is termed the "starting circuit", includes the battery 10, the conductor 11, including the switch 12, the contacts 13 and 13', which constitutes the starting film-controlled switch of the projector, the conductor 15, the contacts 17 and 18 of the phonograph selecting relay A, the conductor 19, the starting solenoid 20 of machine No. 1, and the conductor 21. When this circuit is closed, the starting relay 20 is energized and through it the cage 24 is moved so that the pin 25 rests in the opposite end of the cam slot 26 and in turn operates the resilient operating rod 27, so that the cam 28 projects the clutch arms 29, which in turn causes the double-toothed element 29' thereon to engage one set of the teeth carried by the rotating actuating member B of machine No. 1, all as particularly set forth in my copending application filed October 29, 1927, Serial No. 229,599. Thus the turntable 5 is rotated as the member B is operated simultaneously and synchronously with the projector. At the same time the pickup, or electrical translator 9 moves in the phonic groove of the record, and the circuit for operating the amplifier 33 which is energized is as follows: the alternating current source 31, the amplifying unit 32, the amplifier 33, the conductor 34, the contacts 35 and 36 of the pickup selecting relay C, the conductor 37, the pickup 9, the conductor 38, the contacts 39 and 40 of relay C, and conductor 41. Thus, as the machine No. 1 is operated, the pickup is moved in toward the center, due to the action of the grooves in the sound reproducing record, whereas in recording, this would be operated in the usual manner by feed screw and the like. As the pickup on the end of the arm 7 approaches the end of the phonic groove, the switches S and S' of machine No. 1 are brought into play, one of

these switches being used as a selective means for connecting the film controlled switches 13-14 to in turn control the respective sound recording or reproducing machines and the other for controlling the pickup relay C, so that at the end of the phonic groove of the operating machine the next machine will be made ready to be connected in the amplifying or recording circuit.

- 10 The film controlled switch 14-14' controls the "stop" relays 56 and 56', while the switch 13-13' controls the starting relays 20 and 20', and the circuit for operating the "stop" relay 56 of machine No. 1, is as follows, and includes the battery 10, the conductors 23, 21 and 97, the "stop" solenoid 56, the conductor 98, contacts 100 and 101 of the relay A, the conductor 102 and 61, the contacts 14' and 14, and the conductor 11, including the switch 12.
- 20 When the switch S' of machine No. 1 was closed and the machine No. 1 halted, the coil 67 of the relay A was energized, and the contacts 17-18 and 100-101 were opened and contacts 16-83 and 58-59 were closed, thus placing the switches 13-13' and 14-14' in open circuit with the relays 20 and 56' of machine No. 2, so that when the film closed the switch 13-13', the relay 20' was energized and the turntable 6 was set in motion.
- 30 In this way the switch S' controls through the pickup carrying arm of machine No. 1, the selecting of which machine will be set in motion and stopped next by the film controlled switches. Also by this arrangement the switch S' of machine No. 2, when engaged by its pickup arm will cause the energization of the coil 95 of the relay A, so that the contacts 16-83 and 58-59 will be opened and the contacts 17-18 and 100-101 will be closed, so that the film controlled switches will be selected to control the solenoids 20 and 56 of the machine No. 1 next.

40 The circuit to the starting relay 20' of machine No. 2 includes the battery 10, the conductor 23, the relay 20', the conductor 82, the contacts 83 and 16 of the relay A, the conductor 15, film contacts 13' and 13, and the conductor 11 and switch 12; while that for controlling the "stop" relay 56' includes the battery 10, the conductors 23 and 55, the solenoid 56', the conductor 57, the contacts 58 and 59 of the relay A, conductors 60 and 61, film contacts 14' and 14, conductor 11 and switch 12. Thus it will be seen that the two film controlled switches are so placed as to successively operate the starting and stopping relays of machine No. 1 and then to be selected by machine No. 1, to successively operate the same relays of machine No. 2. It is also evident that machine No. 2 will cause the selection of the film controlled switches for controlling machine No. 1.

50 *Phonograph selecting relay:* The circuits for controlling the phonograph selecting relay A includes, for machine No. 1, the battery

62, the conductor 63 having the manual switch 64, the conductor 65, the switch S' of machine No. 1, conductor 66, coil 67 of the relay A, and conductors 68 and 69. This causes the relay A to bridge contacts 16 and 83 and 58 and 59 and open contacts 17-18 and 100-101 as above set forth, while the energization of coil 95 causes the relay to close switches 17 and 18 and 100 and 101 and open contacts 16-83 and 58-59. The circuit controlled by switch S' of machine No. 2 includes the battery 62, the conductor 63, switch 64, conductors 65 and 93, the switch S' of machine No. 2, conductor 94, the coil 95 and conductors 96 and 69.

55 *Pickup selecting relay:* The circuits controlled by the pickup selecting relay are in turn controlled by the switch S of the respective machines No. 1 and No. 2, the control from machine No. 1 including in its circuit the battery 70, the conductor 71 including the manual switch 72, the conductor 73, the coil 74, the conductor 75, the switch S of machine No. 1, the conductors 76 and 77. The circuit controlled by the switch S of machine No. 2 includes the battery 70, the conductor 71, switch 72, conductors 73 and 78, the coil 79, the conductor 80, the switch S of machine No. 2, and conductor 77. When the coil 74 is energized, the contacts 35 and 36, and 39 and 40 of the relay C are closed and the contacts 84 and 85, and 90 and 91 are opened, while when the coil 79 is energized the contacts 84 and 85, and 90 and 91 are closed and the contacts 35 and 36, and 39 and 40 are opened, this switch S being provided for selectively connecting either one of the pickups 9 or 9' with the recording or amplifying circuit.

60 The switches S or S', as shown in Figs. 2, 3 and 4, are identical in construction, so that the description of one will suffice for both. Each includes a support 42 to which is attached the spring contacts 43 and 44, the latter being provided with a cam recess or edge 45, the purpose of which will presently appear. This entire switch S is connected to and supported by arm 42, to which, in turn, is pivoted the swinging pickup carrying arm 8. Mounted for swinging movement is a shaft 46 which carries the cam shaped weight 47 which is in the path of to be engaged by the arm 8 as the latter approaches the end of the phonic groove. Mounted upon the shaft 46 is an annular member 49 made of a very thin, flexible metal and attached at its lower end to the shaft 46 with its upper end free to move or flex so that, as the weight is moved by the arm 8, the projection 50 engages the under side of the edge 45 of the contact 44, causing the contact to engage the contact 43 for an instant and then release the same, and as the weight 47 is provided with a pin 48, when the rod 8 is moved manually in the opposite direction and engages the arm 52, 120

which is pivoted at 51, the other arm 53 is moved to engage the pin 48 and thus tilt the weight in the opposite direction so that the switch operating member 50 will engage the outer inclined edge of the edge 45 and be flexed and guided away so as not to cause the contact 44 to engage the contact 43. Thus it will be seen that as the arm 8 approaches the end of the phonic groove, both switches S and S' are automatically operated to close their respective contacts 43 and 44, and in turn the various circuits to the coils 74 and 79 of the relay C and the coils 67 and 95 of the relay A, the manual return of the arm 8 re-setting the switch operating the weight 47 in both switches S and S' simultaneously.

Operation.—When the present apparatus is operated in conjunction with a motion picture projector the film of the projector is provided with start and stop devices which may be abutments, perforations or similar devices known in the art, arranged, the one to start at one side of the film and the one to stop at the adjacent side of the film, and where two phonographs are employed on a single film there might be a series of these alternating devices. When everything is ready, and the motion picture machine is started, and previous to the phonograph starting devices being moved into starting position, the operator places the pickup on the disc of machine #1 and when the film starting device has closed contacts 13—13', the electro magnet 20 is energized, and machine #1 is started. This continues until the film carrying device engages contacts 14—14', at which time machine #1 is stopped due to the energization of the electro magnet 56, relay A having bridged contacts 17—18 and 100—101, as electro magnet 95 was energized due to the switch S' of machine #2 having been closed manually or by the arm 8 at the initial starting of the machine. Simultaneously with the stopping of the turntable of machine #1 its arm closes switch S' of machine #1 and causes 67 on relay A to be energized so that contacts 16—83 and 58—59 were closed. Thus, when the next starting film carrying device contacts have operated, the contacts 18—18', the electro magnet 20' is energized and machine #2 is brought into play, and continues to play until stopped by the next closure of contacts 14—14' and which causes the energization of the electro magnet 56' and the halting of turntable of machine #2. Simultaneously with the arm 8 of machine 2, the closing of switch S' of such machine occurs so that the coil 95 of relay A is energized to close contacts 17—18 and 100—101, and the next starting device would set in operation phonograph machine #1. Thus, relay A is a phonograph selecting relay and controlled by the arm actuated switch S' of either machine, the contacts 14—14' causing the stop-

page of the particular phonograph selected by the relay A.

What I claim as new is:—

1. The combination with two film-controlled switches, an electrical sound amplifying circuit and two sound reproducing machines for operation one at a time, of two electrically operated means in circuit with and under the control of said film controlled switches for selectively starting and stopping said sound reproducing machines and means controlled by either of said sound reproducing machines for selecting the film controlled switches for controlling the operation of the other machine. 70

2. The combination with two film-controlled switches, an electrical sound amplifying circuit and two sound reproducing machines for operation one at a time, of two electrically operated means in circuit with and under the control of said film controlled switches for selectively starting and stopping said sound reproducing machines and means controlled by either of said sound reproducing machines for selecting the film controlled switches for controlling the operation of the other machine, and another means also controlled by either sound reproducing machine and particularly by the machine set in motion by the film controlled switch for connecting the sound amplifying circuit to the machine thus selected. 85

3. The combination as set forth in claim 1, in which one of said film controlled switches is for starting the selected machine and the other film controlled switch is for stopping the same machine after the said machine has been operated a predetermined length of time. 100

4. The combination as set forth in claim 2, in which one of the said film controlled switches is for starting the selected machine and the other film controlled switch is for stopping the same machine after said machine has been operated a predetermined length of time. 105

5. The combination as set forth in claim 1, in which the amplifying circuit includes two electrical pickups, one for each sound reproducing machine, and means whereby the pickup of one machine at a time can be connected in said amplifying circuit, said pickup selection being under the control of the last means. 115

6. The combination as set forth in claim 2, in which there is an electrical pickup to each sound reproducing machine, and means whereby one at a time is connected in the amplifying circuit through the last means. 120

7. The combination as set forth in claim 1, in which there are two pickups and a swinging arm carrying each pickup one to each sound reproducing machine, and a normally open switch disposed to be closed by each arm after the arm has been caused to 125 130

travel a predetermined distance to actuate the last switch and cause its pickup to be disconnected from the amplifying circuit and the connection of the remaining pickup to said circuit.

5 8. The combination as set forth in claim 2, in which there is a pickup and a swinging carrying arm therefor to each machine, and two normally open switches to be closed by said pickup carrying arm after the arm has 10 been moved a predetermined distance across the turntable to close two circuits simultaneously to the two last means.

15 9. The combination with two film controlled switches, two sound reproducing machines including two swinging arms, one to each machine, and an electrical pickup carried by each arm, and an electrical amplifying circuit, of a starting and a stopping electrical device for each sound reproducing machine, an electrical film switch selecting relay, and means operated by each of said swinging arms for operating said relay to cause the film controlled switches to be placed 20 in operable relation to the starting and stopping devices of the other machine, or vice versa.

25 10. The combination as set forth in claim 9, characterized by the fact that there is a pickup selecting relay whereby either pickup is connected one at a time with the amplifying circuit, and means operated by each swinging arm for operating said last relay, the swinging arm of one sound reproducing machine causing the operation of the last relay to connect the pickup of the other machine in the amplifying circuit and disconnect the pickup of the remaining machine, and vice versa.

30 40 In testimony whereof I affix my signature.
CHARLES W. EBELING.
